UNITED STATES PATENT OFFICE

113,126

DESIGN FOR A SHOE OR SIMILAR ARTICLE

Aleck E. Wagman, Dorchester, Mass.

Application December 16, 1938, Serial No. 81,825

Term of patent 3½ years

To all whom it may concern:

Be it known, that I, Aleck E. Wagman, a citizen of the United States, residing at Dorchester, in the county of Suffolk and State of Massachusetts have invented a new, original, and ornamental Design for a Shoe or Similar Article, of which the following is a specification, reference being had to the accompanying drawing, forming part thereof.

In the drawing,

Fig. 1 is a perspective view looking toward one side of a shoe or similar article showing my new design; and

Fig. 2 is an elevation looking toward the opposite side of the shoe.

I claim:

The ornamental design for a shoe or similar article, substantially as shown.

ALECK E. WAGMAN.
